UNITED STATES PATENT OFFICE.

WILLIAM J. ADAM, OF NORWOOD, MASSACHUSETTS, ASSIGNOR TO PLIMPTON PRESS, OF NORWOOD, MASSACHUSETTS, A CORPORATION OF MASSACHUSETTS.

SHEET-DELIVERING MECHANISM.

1,187,456.

Specification of Letters Patent. Patented June 13, 1916.

Application filed February 17, 1913. Serial No. 748,907.

To all whom it may concern:

Be it known that I, WILLIAM J. ADAM, a citizen of the United States, residing at Norwood, in the county of Norfolk and 5 State of Massachusetts, have invented certain new and useful Improvements in Sheet-Delivering Mechanism; and I do hereby declare the following to be a full, clear, and exact description of the invention, such as 10 will enable others skilled in the art to which it appertains to make and use the same.

The invention relates to sheet delivering mechanism for printing presses.

The objects of the invention are to provide 15 novel and improved mechanism for enabling the sheets to be delivered either side up, as may be found desirable; to provide novel and improved mechanism for intermittently operating the tapes upon which 20 the sheets are delivered from the impression cylinder and by which they are brought into position to be operated upon by a fly delivery, or to be deposited by the tapes on to the delivery board or table; to provide 25 novel and improved mechanism for controlling the movement of the delivery board or table as the sheets accumulate upon it, so that the top of the pile may be maintained at a substantially uniform height; 30 and to otherwise improve the mechanisms by which the sheets are delivered and properly positioned upon the delivery table.

With these objects in view the invention comprises the features of construction and 35 combinations of parts hereinafter described and set forth in the claims.

The various features of the invention will be readily understood from an inspection of the accompanying drawings and the following 40 detailed description of the mechanisms illustrated therein.

In the drawings Figure 1 is a side elevation showing a delivery mechanism embodying the invention in its preferred form, and 45 so much of a printing press as is necessary to illustrate the application of the delivery mechanism thereto; Fig. 2 is a diagrammatic view indicating one form of mechanism through which the delivery table may be 50 lowered; Fig. 3 is a plan view of the parts shown at the left in Fig. 1; Fig. 4 is a side elevation, partly in section, of the mechanism shown in Fig. 3; Fig. 5 is a detail plan view showing a part of the sheet jog- ging mechanism; Fig. 6 is a sectional detail 55 showing a part of the mechanism for operating the joggers; Fig. 7 is a rear elevation of the mechanism shown in Fig. 3, certain parts being shown in section, and other parts being broken away for the sake 60 of clearness; Fig. 8 is a detail view showing the devices for coupling the fly-finger shaft to its actuating mechanism; Fig. 9 is a diagrammatic view indicating the position of certain of the parts when the fly 65 delivery is in action; Fig. 10 is a diagrammatic view showing the arrangement of the delivery tapes when the fly delivery is in action; Fig. 11 is a diagrammatic elevation indicating the position of certain of the 70 parts when the fly delivery is inactive and the tape delivery is in operation; Fig. 12 is a diagrammatic view showing the position of the tapes when the parts are in the position indicated in Fig. 11; Fig. 13 is a 75 detail elevation, partly in section, showing the mechanism for intermittently operating the delivery tape; Fig. 14 is a plan view, partly in section, of the devices shown in Fig. 13, the parts being shown in a different 80 position; Fig. 15 is a sectional detail through the axis of the shaft carrying the driven tape carrying rolls; Fig. 16 is a diagram indicating the arrangement of the parts for operating the tapes; Fig. 17 is a 85 detail section similar to Fig. 15, showing the parts in a different position; Fig. 18 is a detail of the brake mechanism for the tape 90 roll shaft; Fig. 19 is a detail of the slotted disk through which the tape roll shaft is actuated; Fig. 20 is a detail of the 95 brake operating devices; Fig. 21 is a plan view showing the preferred form of mechanism for controlling the movement of the delivery table; Fig. 22 is a side elevation of the parts shown in Fig. 21; Fig. 23 is a partial plan view showing the mechanism through which the lowering of the 100 delivery table is controlled from the top of the pile; Fig. 24 is a sectional detail on line 24-24, Fig. 23; Fig. 25 is a sectional detail on line 25-25, Fig. 23; Fig. 26 is a rear elevation of the parts shown in Fig. 21; Fig. 27 is a side elevation of the controlling mechanism shown in Fig. 105 23; Fig. 28 is a sectional detail through the axis of the clutch by which the delivery table is lowered; Fig. 29 is a sec-

tional elevation on line 29-29, Fig. 28; and Fig. 30 is a sectional view on line 30-30, Fig. 28.

In the mechanism illustrated in the drawings, 1 indicates the impression cylinder of a two-revolution cylinder printing press, which may be of any usual and well-known construction. The sheets, after being carried around the impression cylinder and receiving the impression from the printing form, are stripped from the cylinder by the usual strippers 2, and are guided on to the delivery tapes 3 upon which they are held by the upper tapes 4. In case the sheets are to be delivered printed side down they are carried by the tapes into position over the fly-fingers 5, and are delivered by the fly-fingers on to a vertically movable delivery board 6. If the sheets are to be delivered printed side up, they are carried by the tapes 3 into position over the delivery board, and are delivered directly on to the board by the tapes. In order that the sheets may be delivered in either way as may be desired, provision is made for rendering the fly-fingers and their operating mechanism inactive when the tapes are operated to deliver the sheets directly on to the delivery board, and to render the mechanism which thus operates the tapes inactive when the fly-fingers are to deliver the sheet. As the sheets pass from between the tapes 3 and hold-down tapes 4, they are subjected to a blast of air from a pipe 4' which extends transversely above the tapes just beyond the rolls which support the rear ends of the tapes 4. The pipe 4' is provided with a series of perforations which are so located that the jets of air escaping from the pipe are directed against the upper surface of the sheet at an inclination in the direction of the feed. The air blast therefore not only tends to hold the sheet down upon the tapes, but also counteracts any tendency of the front edge to curl up, since the air blast, as it strikes the top of the sheet, is directed along its upper surface in the direction of the feed. It also dries the ink to avoid offset.

50 The delivery tapes pass over rolls 7 secured to a shaft 8 arranged adjacent to the impression cylinder and intermittently driven through mechanism which will be hereinafter described. From the rolls 7 the upper or sheet supporting runs of the tape lead to a series of rolls 9, thence in a reverse direction to rolls 10, thence in a forward direction to rolls 11, from which they return to the rolls 7. Guide rolls 12 may be arranged to engage the tapes between the rolls 9 and the rolls 10 or 7, and guide rolls 13 may be arranged to engage the tapes between the rolls 11 and 7, as illustrated in Figs. 10 and 12. When the sheets are to be delivered by the fly-fingers the tape sup-

porting rolls remain in the position indicated in Fig. 10 during the operation of the press, and act to bring the sheets successively into position over the fly-fingers by which they are taken from the tapes and delivered on to the delivery board. When the sheets are to be delivered by the tapes directly on to the delivery board, the tape rolls 9 and 10 are advanced from the position indicated in Fig. 10 to the position indicated in Fig. 12 during the forward travel of the tapes to carry a sheet into position over the delivery board, and then these rolls are returned to the position indicated in Fig. 10, during which return movement the tapes pass from under the sheet and deposit it upon the pile on the delivery board.

In order that the tape rolls 9 and 10 may be moved forward and back when it is desired to deliver the sheets printed side up, the rolls 9 are secured upon a shaft 14 mounted in a movable carriage, and the rolls 10 are mounted in a cross-bar 15 connected to or forming a part of the carriage. In the construction shown, the carriage for the roll shaft 14 comprises two side plates 16 in which the opposite ends of the shaft 14 are journaled. Each side plate is mounted to move on guideways 17, and is provided with rolls 18 running on the upper edge of the guideway, and with a roll 19 engaging the under side of the guideway. The bar 15 is connected by rods 20 with the side plates 16, and is supported by rolls 21 running on the flanges 22 of the side bars 23 which form a part of the supporting frame work. The side plates 16 of the tape roll carriage are connected by links 24 with the upper ends of arms 25 which are secured to a transverse rock shaft 26. The rock shaft 26 is actuated to move the tape roll carriage forward and back at proper intervals during the operation of the machine through an arm 27 secured to one end of the rock shaft 26, and connected by a link 28 with a crank arm 29 mounted on a cam shaft 30 of the printing press. The crank arm 29 may be clamped to the cam shaft, or the clamping means may be loosened so that the arm is loose on the shaft, according to the manner in which the sheets are to be delivered. When the crank arm is clamped to the cam shaft, the tape roller carriage will be reciprocated to deliver the sheets. If the fly-delivery is to be used, the crank arm is unclamped from the shaft, so that the mechanism for reciprocating the tape roller carriage becomes inactive, and the tape rolls remain in the position indicated in Fig. 10 during the operation of the press.

When the mechanism for reciprocating the tape roll carriage is rendered inactive, the sheets are delivered by the fly-fingers 5 over which they are positioned by the tapes 13.

3. The fly-fingers are secured to a shaft 31 mounted in arms 32 provided with hubs surrounding a transverse rod 33. The arms are also provided with yokes 34 adapted to 5 embrace the shaft 26 when the fly-finger shaft is in active position, as indicated in Figs. 4 and 9. When the arms are in this position they are rigidly secured to the rod 33 by clamping screws 35, and are secured 10 to the shaft 26 by clamping screws 36. The arms and clamping screws 36 also serve to firmly lock the rock shaft 26 against movement, and to therefore retain the tape roll carriage in the position indicated in Figs. 15 4, 9 and 10. When the sheets are to be delivered by the reciprocation of the tape roll carriage, the arms 32 are swung up from the position indicated in Fig. 9 to the position indicated in Fig. 11, thus freeing the rock 20 shaft 26 and raising the fly-finger shaft 31 up out of the path of the tape roll shaft 14. The arms are secured in this position by the clamping screws 35 which engage the fixed rod 33. When the fly-finger shaft 25 is raised into this position it may also be turned to bring the fly-fingers into position above the path of the tape rolls 9, as indicated in Fig. 11, and be secured in this position by tightening the clamping screws 30 37, indicated in Fig. 7. When the fly-fingers are in this position they act as guides to hold the sheets down on the tapes as the tape rolls 9 move forward and back.

In order that the fly-finger shaft may be 35 moved into and out of active position, as above described, a coupling is provided for connecting the shaft with the actuating shaft 28 through which the fly-fingers are actuated. The actuating shaft 38 is so 40 mounted that it is in line with the fly-finger shaft 31 when the fly-finger shaft is in its active position, and the ends of the shafts are provided with an interlocking tongue and slot 39 which are in engagement when 45 the fly-finger shaft is in active position. The coupling slot and tongue 39 is maintained in engagement by a sleeve 40 mounted on the shaft 38 and connected therewith by a spring pin 41 adapted to engage one of 50 two annular grooves 42 formed in the shaft. When the shaft 38 is coupled with the fly-finger shaft, the sleeve is slid forward to cover the coupling, and is retained in this position by the engagement of the pin 41 with one of the grooves 42, as indicated in 55 Fig. 7. When the fly-fingers are to be rendered inactive, and the fly-finger shaft is to be uncoupled from its actuating shaft 38, the sleeve 40 is moved back to uncover the coupling 39 so that the shaft 31 may be raised into its inactive position, the sleeve being held in retracted position by the engagement of the pin 41 with the other groove 42. 60 The shaft 38 is rocked at proper intervals 65 during the operation of the press through

a cam 43 secured to the cam shaft 30, and operating upon a lever 44, the upper end of which is connected to a slide bar 45. The upper end of the slide bar 45 is guided in a support 46, and is provided with a rack 70 engaging a pinion 47 on the end of the shaft 38.

The tapes 3 are advanced during the time that the sheets are being stripped from the impression cylinder, and then remain stationary until the succeeding sheet is to be transferred from the cylinder on to the tapes. The delivery table is arranged at such a distance from the impression cylinder that there are several sheets upon the 75 delivery tapes when a sheet is in position to be taken up by the fly-fingers. The sheets remain upon the tapes, therefore, during the interval required for printing and delivering several sheets, and are therefore in better condition to be delivered upon the pile than would be the case if the sheets were delivered to the fly-fingers by continuously running tapes. The shaft 8 carrying the tape rolls 7 is rotated intermittently to advance the tapes at the proper intervals through a clutch sleeve 48 keyed to ride with and slide on the shaft and provided with clutch teeth adapted to be engaged with corresponding clutch teeth on the hub 80 of a gear 49 which is mounted to turn freely on the shaft (Figs. 13 to 20). The gear 49 is continuously driven during the operation of the press from a gear 50 through intermeshing gears 51. The gear 50 is formed 85 on a drum 51 connected with the gear 52 through which the impression cylinder is rotated, or with the shaft of the impression cylinder. The clutch sleeve 48 is provided with an annular groove 53 engaged by ribs 100 formed on the two brake blocks 54 and 55. The brake blocks are held in position on the clutch sleeve by bolts 56, one of which carries a cam collar 57 adapted to cooperate with clamping cams formed on an arm 58. 105 The clamping arm 58 is connected by a link 59 with a fixed pin 60 on the bearing 61 for the clutch sleeve and the clutch blocks are held from rotation by this connection. When the clutch sleeve is moved into the position indicated in Fig. 17 to engage the clutch and thus connect the roll shaft 8 with the actuating gearing, the clamp arm 58 is moved to release the brake blocks, so that the clutch sleeve and shaft are free to rotate. 110 When the clutch sleeve is moved to disengage the clutch, the clamping arm is actuated to force the brake blocks toward each other, and thus apply a braking friction to the clutch sleeve, which immediately arrests 115 the rotation of the shaft and holds it in fixed position. The clutch sleeve is moved to engage the clutch and release the brake, by a disk 62 loosely mounted on the shaft 8, and provided with a spring cam plate 63 and 120

ranged to engage a roll 64 carried by the lower brake block 55. The disk is also provided with a rigid projection 65 at the end of the spring cam plate for holding the 5 clutch in engagement. The clutch sleeve is moved to disengage the clutch by a cam block 66 secured to the drum 51. The cam carrying disk 62 is provided with four radial slots 67 adapted to be engaged by two 10 actuating rolls 68 and 69 carried by the drum 51, and is provided with locking surfaces 70 adapted to coöperate with the surface of the drum 51 in retaining the disk 62 in the position into which it is turned by 15 the engagement of the rolls 68 and 69 with the radial slots 67.

The impression cylinder makes two revolutions in printing and delivering each sheet, and during these two revolutions of 20 the cylinder the rolls 68 and 69 turn the cam disk 62 through a complete revolution. The roll 68 is fixed to the drum 51 in such a position that it will engage and turn the cam disk 62 to engage the tape actuating 25 clutch as the front edge of the sheet is transferred by the strippers 2 from the impression cylinder to the tapes. The cam block 66 is so arranged that it will disengage the clutch after the rear edge of the sheet has 30 passed on to the tapes, and the roll 69 is arranged a short distance in advance of the cam block 66. The roll 69 and the cam block 66 may be adjusted so that the advance movement of the tapes will be 35 arranged when the sheet is brought into proper position above the fly-fingers in case the fly delivery is being used, or when the sheet has been brought into proper position over the delivery table when the reciprocating tape 40 delivery is being used.

Assuming that the tape actuating clutch is disengaged, and that a sheet is about to be transferred to the tapes, the roll 68 engages one of the slots 67 in the cam disk 45 62 and turns the disk through a quarter revolution. During this movement of the disk the spring cam plate 63 rides against the roll 64 and forces the clutch teeth yieldingly into engagement, and brings the lug 50 65 into engagement with the roll to retain the clutch in engagement. The tape roll shaft 14 is now rotated to advance the tapes until the sheet has been transferred, or nearly transferred to the tapes. The roll 55 69 then engages one of the slots in the cam disk and turns the disk through a second quarter revolution. This movement of the disk disengages the lug 65 from the roll 64 so that the clutch is free to be disengaged. 60 The clutch is then free to be disengaged by the cam block 66 as it travels past the roll 64. After the clutch is disengaged by the cam disk 64 the tapes remain stationary until the clutch is again engaged. During 65 the rotation of the impression cylinder, following the delivery of a sheet, the rolls 68 and 69 turn the cam disk through a half revolution, bringing it back to initial position, so that the cam 63 will be in position to again engage the clutch when the roll 70 70 turns the cam disk during the next sheet delivering revolution of the impression cylinder.

The delivery board or table 6 upon which the sheets are delivered is carried upon vertically movable heads 71 guided upon vertical side rods 72 and raised or lowered by vertical screws 73 engaging nuts carried by the heads. The raising and lowering screws 73 are connected by bevel gears 74 with 75 side shafts 75 which are in turn connected by bevel gears 76 with a transverse shaft 77 so that the screws turn in unison to simultaneously raise and lower the heads 71.

The sheets delivered by either the fly or the reciprocating tape delivery are properly positioned upon the delivery table, or upon the top of the pile carried by the delivery table, by jogging devices arranged to embrace the upper part of the pile. As shown, the jogging devices comprise front and rear jogging boards 78 and 79, and side jogging boards 80. The front jogging board 78 is carried by arms 81 which are provided with hubs 82 mounted to slide 85 upon the shafts 75. The rear jogging board is carried by arms 83 adjustably secured on rods 84 which are mounted to slide in bearings 85. The side boards are carried by rods 86 mounted to slide in bearings 87. 90 The supporting rods 84 and 86 are connected by bell crank levers 88 pivoted upon fixed supports 89 and provided at their ends with slots engaging pins carried by collars 90 which are adjustably secured to the supporting rods. The supporting rods 84 for the rear jogging board are connected with the front jogging board by levers 91 pivoted upon fixed supports 92 and provided with slots in their ends engaging pins carried by lugs 93 and collars 94 on the arms 81 and supporting rods 84 respectively. Through the connections described the jogging boards are moved in unison when they are actuated to jog and position the top of 95 the pile. The jogging boards are yieldingly held in advanced position where they retain the top of the pile in proper position with relation to the delivery board by 100 springs 95 interposed between the hubs of 105 the gears 6 and the hubs 82 of the arms which support the front jogging board 78. When the sheets are being delivered by the fly-fingers, the jogging devices are retracted during the delivery of each sheet by arms 110 96 secured to the fly-finger shaft 31, and provided with rolls 97 at their outer ends 115 adapted to engage and swing the arms 91 during the latter part of the delivery stroke of the fly-fingers. When the sheets are be- 120

125 130

ing delivered by reciprocating the tape roller carriage, the arms 91 are operated during the delivery of each sheet to retract the jogging boards by arms 98 secured to the rock shaft 26, and provided with rolls 99 adapted to engage shoulders 100 formed on links 101 which are connected with the arms 91. The links 101 are supported and guided by plates 102 which ride on the shaft 26, and are slotted to straddle the arms 98.

The delivery board may be lowered as the pile of sheets accumulate to keep the top of the pile in proper relation to the delivery 15 and jogging devices either manually or automatically. If the delivery mechanism is used in connection with a machine provided with mechanism for automatically feeding sheets to the press from a vertically movable feed table, the screws 73 may be conveniently actuated to automatically lower the delivery table by connecting one of the shafts 75 with the mechanism indicated 20 diagrammatically at 103 in Fig. 2 through which the upward movement of the feed table is controlled to maintain the top of the pile on the feed table in proper relation to the sheet separating and feeding devices. It is preferred, however, to provide 25 means for automatically lowering the delivery table which is controlled from the top of the pile on the delivery table so that the top of the pile is automatically maintained in proper relation to the delivery devices 30 as the sheets accumulate. The preferred form of such mechanism is shown in Figs. 21 to 30. As here shown, one of the shafts 75 is connected through gears 104 with a shaft 105 which is intermittently actuated to 35 turn the screws 73 and thus lower the delivery table. The shaft 105 is actuated at intervals through a gear 106 loosely mounted on the shaft, and carrying an annular flange 107 forming one member of a clutch, the 40 other member of which is a sleeve 108 loose on the shaft. During the normal running of the machine the sleeve 108 is connected with the shaft through a gear 145 keyed to slide on the shaft for a purpose to be explained later, and provided with clutch lugs 45 146 coöperating with clutch lugs 147 on the sleeve. The clutch is a form of Horton clutch in which the clutch rolls 109 are interposed between the inner surface of the flange 50 107 and wedging surfaces 110 formed on the sleeve 108. The rolls are arranged between the lugs 111 of the roll carrying ring 112 which is connected with the clutch sleeve 108 by a spring 113 tending to turn the ring 55 in a direction to wedge the rolls between the surfaces 110 and the inner surface of the flange 107. The wedge surfaces 110 are so arranged that the gear 106 may turn idly in one direction when the clutch is engaged, 60 but will be clutched to the shaft to turn 65

the shaft when moving in the opposite direction. The gear 106 is oscillated during the operation of the press by means of a rack 114 pivoted to the upper end of the reciprocating rod 45 and engaging a gear 70 115 which in turn engages the gear 106. The roll carrying ring 112 of the clutch is provided with a tooth 116 arranged to engage a stop 117 carried by a pivoted arm 118. When the stop tooth is in engagement with 75 the stop, the roll carrying ring is held against rotation, and the clutch is out of engagement or inactive. The stop 117 is preferably in the form of a lever pivoted to the arm 118 and connected to the arm by a 80 spring 119 which tends to turn the roll carrying ring in a direction against the tension of the spring 113, so that the rolls are maintained in the inactive part of the surfaces 110, and do not tend to wedge between the surfaces and the flange 107 so long as the stop tooth on the ring is in engagement with the stop on the arm 118. When the stop arm 118 is operated to release 85 the roll carrying ring, the clutch is rendered active, and the shaft 105 is turned through a single revolution, and then the clutch is disengaged by the reengagement of the stop tooth with the stop arm through mechanism controlled from a controller finger 120 which is engaged with the top of the pile after the delivery of each sheet. The controller finger is secured upon a rock shaft 121 mounted on one of the side jogging boards 80 and connected by gears 122 90 with a rock shaft 123. The gear 122 on the rock shaft 123 is keyed to slide on the shaft as the jogging board is moved forward and back. The rock shaft 123 carries an arm 124 which is provided with a segmental surface 125 arranged to support a coupling finger 126. The finger 126 is mounted to slide and turn on a pin 127 which passes through a slot in the finger, and the lower end of the finger is held in engagement with the segment 125 by a spring 128 which tends to draw the finger downward. When the finger is supported upon the segment 125 its upper end lies between two 95 slide bars 129 and 130. The bar 129 is arranged to engage a projection on the stop arm 118, and the bar 130 is reciprocated at regular intervals during the operation of the press through a lever 131, the upper end of which is arranged to engage the bar, and 100 the lower end of which carries a roll 132 arranged in the path of a cam 132 on the rock shaft 38. The lever is operated by the cam to advance the bar 130 during the delivery 105 of each sheet.

The arm 124 and rock shaft 123 are moved in a direction to engage the controller finger 120 with the top of the pile through a spring 133 connected with the free end of a link 134 which is supported upon a fixed pin 135 110

135 and is connected with the arm 124. The arm 124 is moved in a direction to raise the controller finger from the pile so that the succeeding sheet may be properly positioned 5 on the pile by an arm 136 carried by the shaft 38, and provided with a slot 137 adapted to engage a roll 138 on the link 134. During the delivery of each sheet the arm 124 will be moved toward the right in Fig. 10 27 by the actuating arm 136 on the shaft 38, thus raising the controller finger from the pile. During the backward stroke of the shaft 38 and arm 136 the arm 124 will be moved toward the left in Fig. 27 by the 15 spring 133 until the controller finger engages the top of the pile, when further movement of the arm 124 toward the left will therefore depend upon the 20 height of the pile, the movement decreasing as the height of the pile increases. So long as the top of the pile is above a predetermined point, therefore, the segment 125 will remain under the coupling finger 126 when 25 the arm 124 completes its movement toward the left, and the upper end of the coupling finger will remain between the slide bars 130 and 129, so that motion will be transmitted from the bar 130 to the bar 129 when the 30 bar 130 is advanced, and the stop arm 118 will be operated to render the table lowering clutch active. The clutch will be rendered active and the actuating shaft 105 will be given a single revolution during the 35 delivery of each sheet so long as the top of the pile is above a predetermined point. When the intermittent lowering of the delivery table carries the top of the pile below a predetermined point, the movement of the 40 arm 124 toward the left in Fig. 27 will be sufficient to carry the segment 125 from below the lower end of the coupling finger 126, so that the finger will be drawn down by its spring 128, thus uncoupling or rendering 45 inactive the mechanism for rendering the clutch active. When this occurs, the slide bar 130 will move idly forward when actuated by the cam 132, and the table lowering clutch will remain inactive. When the coupling finger 126 moves downward, its lower 50 end is brought in front of the segment 125, so that the finger is swung about its pivot as the segment arm 124 is moved toward the right. As the segment arm completes its 55 movement in this direction, the lower end of the coupling finger engages a notch 139 in the segment, so that on the return movement of the segment the coupling finger is swung about its pivot and raised into the 60 position indicated in Fig. 27, after which it rides on the segment 125 during the continued return movement of the segment arm, and either remains in its upper position or 65 drops off the end of the segment, according to the height of the pile. Thus through the

mechanism described the mechanism for lowering the delivery table is controlled by the controller finger 120, the mechanism being rendered active to lower the pile when the top of the pile is above a predetermined point, and being rendered inactive whenever the top of the pile is below this point. 70

In order that the delivery table may be rapidly raised or lowered when desired, the machine is provided with an electric motor 75 140, the shaft of which is connected through reversing gearing 141 with a gear 142 secured to the outer end of the shaft 143, the inner end of which is provided with a gear 144 adapted to mesh with the gear 145 when 80 it is drawn back to disconnect the automatic clutch from the shaft 105. During the normal running of the machine the gear 145 is forward out of mesh with the gear 144 and with the clutch lugs 146 and 147 in engagement. When the motor is to be used to raise or lower the delivery table, the gear 145 is moved back on the shaft to disengage the clutch lugs and to bring it into mesh with gear 144, and thus connect the gear 144 with 85 the shaft 105. 90

While it is preferred to employ the construction and arrangement of parts shown and described, it will be understood that this construction and arrangement is not essential, and may be varied and modified without departing from the broader features of the invention. 95

Having explained the nature and object of the invention, and specifically described one form of mechanism in which it may be embodied, what is claimed is:— 100

1. A sheet delivering mechanism, having, in combination, a fly-delivery including a fly-finger shaft, a reciprocating tape-delivery including reciprocating tape supporting rolls, means for supporting the fly-finger shaft either in the path of the rolls, or out of the path of the rolls and with the fingers extending above the path of the rolls to act 110 as a guide for the tapes, and means for reciprocating the tape supporting rolls or retaining them in fixed position. 105

2. A sheet delivering mechanism, having, in combination, a reciprocating delivery, a fly-delivery including a fly-finger rock shaft, arms carrying the rock shaft, an actuator shaft, means for holding the arms with the shafts in line or with the fly-finger shaft in 115 a higher plane, and means for coupling or uncoupling the shafts. 120

3. A sheet delivering mechanism, having, in combination, a reciprocating tape-delivery including two sets of fixed tape rolls, a tape roll carriage carrying two sets of tape rolls and tapes looped about the fixed and movable rolls, mechanism for reciprocating the carriage or retaining it in fixed position, a fly-delivery to which the sheets are presented by the tapes when the carriage is in 125 130

- fixed position, and means for rendering the fly-delivery active or inactive.
4. A sheet delivering mechanism, having, in combination, a vertically movable sheet receiving table, a tape delivery comprising two series of fixed tape rolls, a reciprocating roll carriage carrying two sets of tape rolls, and tapes looped over the fixed and movable rolls, mechanism for reciprocating the carriage or retaining it in fixed position, a fly delivery to which the sheets are presented by the tapes when the carriage is in retracted position, and means for rendering the fly delivery active or inactive.
5. A sheet delivering mechanism, having, in combination, a tape delivery comprising a series of fixed tape rolls 7, a second series of fixed tape rolls 11, a reciprocating roll carriage carrying the tape rolls 9 and 10, tapes looped about the rolls 7, 9, 10 and 11, mechanism for reciprocating the carriage or retaining it in retracted position, a rock shaft 31 carrying fly fingers and arranged adjacent rolls 9 when in retracted position, means for holding the shaft 31 in fixed position for delivery of sheets to the fly fingers or in position above the path of the rolls 9, and mechanism for rocking the shaft 31 which may be rendered active or inactive.
6. A sheet delivering mechanism, having, in combination, an impression cylinder, a fly-delivery, sheet conveying tapes leading from the impression cylinder to the fly delivery of a length to support a plurality of sheets, and mechanism for intermittently advancing the tapes to bring the sheets carried thereby successively to the fly-delivery.
7. A sheet delivering mechanism, having, in combination, an impression cylinder, tapes to which the sheets are delivered, a series of tape supporting rolls mounted in fixed position adjacent to the cylinder, tape actuating mechanism including a clutch, mechanism for engaging the clutch during the delivery of the sheets to the tapes and 45 for disengaging the clutch after each sheet has passed on to the tapes.
8. A sheet delivering mechanism, having, in combination, an impression cylinder, tapes to which the sheets are delivered, tape 50 actuating mechanism including a clutch, a cam disk for engaging the clutch provided with radial slots, projections connected to move with the impression cylinder for successively engaging the slots, and a cam connected to move with the impression cylinder for disengaging the clutch.
9. A sheet delivering mechanism, having, in combination, an impression cylinder, 60 tapes to which the sheets are delivered, a shaft adjacent the impression cylinder carrying tape supporting rolls, a gear connected to move with the impression cylinder, a clutch member on the shaft driven from said gear, a coöperating clutch member connected to rotate with the shaft, a drum connected to rotate with the impression cylinder, a disk loosely mounted on the shaft and provided with a cam for engaging the clutch members and with four radial slots and intermediate locking segments, two rolls carried by the drum for successively engaging the slots in the disk, and a cam block carried by the drum for disengaging the clutch members.
